MECHANICAL PENCIL

Charles R. Keeran, Evanston, Ill., assignor, by
mesne assignments, to Eagle Pencil Company,
Inc., New York, N. Y., a corporation of Dela-
ware

Application February 14, 1931. Serial No. 515,684

11 Claims. (Cl. 120—18)

This invention relates to mechanical pencils of the type in which the lead is both propelled and withdrawn positively by operation of the mechanism, and which includes a magazine for spare leads and a holder in which an eraser is removably carried. The invention consists in certain improvements in the mechanism and in the means for mounting it in the barrel of the pencil, designed to facilitate assembly and disassembly, so that minor repairs can be readily made by the user or by the dealer without the necessity of shipping the device back to the factory. The invention therefore comprises certain features and elements of construction herein shown and described, as indicated by the appended claims.

In the drawing:

Figure 1 is an axial section on a scale somewhat larger than the actual size of the article, and showing the pencil equipped with a mechanism embodying this invention.

Figure 2 is an axial section on a still larger scale, showing the lower end portion of the pencil and the lead-propelling mechanism therein.

Figure 3 is a sectional view similar to Figure 2, showing the propelling mechanism in position after ejecting a lead.

Figure 4 is a transverse section taken as indicated at line 4—4 on Figure 2.

Figure 5 is a side elevation partly in section of the guide tube for the lead-propelling plunger with the spare lead chamber and eraser socket which are associated therewith.

Figure 6 is a detail view of the lead-propelling carrier and plunger.

While the mechanism herein illustrated and its manner of operation are familiar in a general way, the particular arrangement of the parts and their assembly in the pencil barrel has been worked out to insure satisfactory operation, but particularly to simplify repairs or adjustments which may occasionally be required and to provide for taking up wear in the working parts. As illustrated, the pencil barrel, 1 is formed with a bore at 2, in which the spirally slotted tube, 3, is accommodated. The lower end of this tube, 3, is tightly secured in a sleeve, 4, which itself is forced into an enlarged bore, 5, of the barrel adjoining the bore, 2. This anchors the spiral tube, 3, in the barrel as a permanent fixture therein. Journaled within the tube, 3, for rotation about its axis is the slotted tube, 6, which is permanently anchored in the lower end of a cylindrical chamber, 7, serving as a spare lead magazine, as indicated in Figure 1, and the upper end of said chamber, 7, is surmounted by an enlarged cylindrical

portion, 8, which functions as a socket to receive the metallic holder, 9, in which the removable eraser, 10, is carried. The cylindrical parts, 7 and 8, may be made integral by a familiar drawing process, such as is employed in the manufacture of cartridge shells, and the slotted tube, 6, may be attached to the part, 7, in any suitable manner, as by flaring and swedging over its extreme end in the form of a flange, 6^a, opposing the slight shoulder, 6^b, which abuts the outer or lower side of the bottom wall of the cylinder, 7. Since the tube, 6, is hollow, a disk, 11, will be inserted to form a closed bottom wall for the magazine chamber, 7.

At the opposite or lower end the slotted tube, 6, is threaded to receive a retaining nut, 12. The fixed sleeve, 4, provides at its outer end a shoulder, 14, which serves as a stop for the nut, 12, and preferably a washer, 13, is interposed between the nut and said shoulder to facilitate rotation of the tube, 6. At the upper end of the barrel a metallic bushing, 15, is inserted into a counterbore, 16, with its flange, 15^a, engaging the upper end of the barrel, 1. This bushing serves as a journal bearing for the tubular part, 7, while its flange, 15^a, provides a stop shoulder for engaging the transverse wall, 8^a, of the eraser socket, 8. Thus, by proper adjustment of the nut, 12, the rotative member, consisting of parts, 6, 7 and 8, may be secured in the barrel, 1, with the stop shoulders accurately related to permit relative rotation of the parts without appreciable end play. Preferably, the nut, 12, and the end of the tube, 6, are formed with a tapered thread somewhat similar to a pipe thread, so that the nut will hold tightly without any tendency to back off, but may be threaded somewhat farther on to the sleeve, 6, for taking up wear if required.

The lead, indicated at 17, is held in a familiar manner by the frictional grip of a hollow plunger, 18, whose end is slightly flared at 18^a by reaming to facilitate insertion of the blunt end of the lead therein. At its opposite end the plunger, 18, is formed with a laterally projecting lug, 19, which extends through the slot, 20, of the tube, 6, and into the spiral slot, 21, of the tube, 3. Thus, when the tube, 6, is rotated, the lug, 19, is forced to traverse the spiral slot, 21, causing the plunger, 18, to slide longitudinally within the tube, 6, and move the lead through the tip, 22. The frictional grip of the hollow plunger, 18, upon the end of the lead, 17, permits the plunger to withdraw the lead within the barrel as well as to propel it outwardly through the tip, 22, depending on the direction of rotation of the tube, 6.

However, the propulsion of the lead outwardly is assisted by the presence of a solid plunger, 23, within the hollow plunger, 18, and provided with a lug, 24, which also engages the spiral slot, 21, of the tube, 3. The lugs, 19 and 24, are longitudinally spaced apart, and as shown, this spacing is such that they engage consecutive turns of the slot, 21. When the lead is so nearly used up that only a short piece remains in the tip, 22, and 10 plunger, 18, the plunger will have traveled its full range into the bore, 25, adjacent the shoulder, 26, of the tip, 22, and at this position the lug, 19, will be rested against the inner shoulder, 4^a, of the sleeve, 4. Further rotation of the sleeve, 6, is 15 permitted by the terminal portion, 21^a, of the slot, 21, which is formed at right angles to the axis instead of obliquely, like the helical portion, and while the lug, 19, is swinging through a partial turn through this terminal portion, 21^a, the lug, 20 24, continues to traverse the adjacent spiral portion, thus moving the plunger, 23, downwardly within the hollow plunger, 18, and ejecting the fragment of lead, 17^a, therefrom, as indicated in Figure 3.

25 As shown in Figure 1, the pencil may be provided with a pocket clip, 30, which is in general of the usual design, having a ball end, 31, formed on its spring tang which extends along the barrel, 1, near its upper end. The tang is offset at 32 to pass through an aperture, preferably in the form 30 of a slot, 1^a, in the barrel, and within the barrel a terminal portion, 33, extends against the wall of the counterbore, 16. For locking the clip in this position the bushing, 15, is reduced at its 35 inner end at 15^b, forming an annular groove in which the extreme end of the terminal, 33, is engaged. This groove having a depth substantially equal to the thickness of the stock at 33, holds the clip firmly, because its transverse portion, 32, is checked against movement by engagement with the walls of the slot, 1^a. However, if the 40 clip should break or become bent, it may be quickly removed from the barrel by simply withdrawing the bushing, 15, so as to release the 45 part, 33.

In fact, the removal of any part of the mechanism except the spirally slotted tube, 3, is readily 50 accomplished by unscrewing the nut, 12, which releases the rotative element comprising the tubular parts, 6, 7 and 8. Since the slot, 20, extends through the threaded end of the tube, 6, this rotative element may be withdrawn upwardly 55 through the barrel as soon as the nut, 12, and washer, 18, are taken off. If these parts are first turned counter-clock-wise far enough to feed the plungers, 18 and 23, to the upper end of the spiral tube, 3, the latter will drop out of the barrel readily, or may even remain frictionally engaged with the tube, 6; otherwise, the 60 removal of the tube, 6, will permit the plunger lugs, 19 and 24, to be disengaged from the slot, 21, by reason of the extra clearance afforded in the tube, 3, and these small parts can be easily shaken out of the barrel.

65 The tip, 22, is shown screwed onto the threaded end of the sleeve or bushing, 4, at 22^a, and thus forms a removable housing for the nut, 12, serving to prevent any disturbance of the adjustment of the nut when the parts are assembled. 70 It is well understood that when the barrel, 1, is made of celluloid or like material it is sometimes subject to a gradual shrinkage, tending to shorten its length; in this event the threaded engagement of the tip, 22^a, will permit it always to be 75 screwed tightly against the lower end of the bar-

rel, and the variation in the total length may be compensated for by adjustment of the nut, 12, to bring the shoulder, 8^a, into snug working engagement with the shoulder, 15^a, of the bushing, 15. The bushing, of course, may be forced farther 80 into the barrel if the material of the latter should shrink away from the flange, 15^a, as the barrel ages.

I claim:

1. In a pencil comprising a tubular barrel and a tip thereon, a lead-propelling mechanism, means located near the tip securing said mechanism within the barrel and means securing the tip to the barrel independent of the means securing the propelling mechanism. 85

2. In a pencil comprising a tubular barrel and a lead-operating mechanism functioning therein, means for locking said mechanism in said barrel, a tip detachably secured to the barrel independently of said mechanism locking means, said locking means being accessible upon detachment of the tip and operable at will for release removal of the lead-operating mechanism. 95

3. In a mechanical pencil comprising a tubular barrel and a lead-operating mechanism functioning therein, a removable tip for the writing end of the pencil and a nut housed in said tip securing said mechanism in said barrel. 100

4. In a mechanical pencil comprising a barrel and a lead-feeding mechanism functioning 105 therein, and means for locking said mechanism in operative position in said barrel, said locking means having a bore to permit the lead to be fed therethrough.

5. In a mechanical pencil comprising a tubular barrel, a lead-operating mechanism functioning therein, a tubular lead magazine forming the upper part of said operating mechanism, said magazine being enlarged at its outer end to form a head for the pencil and serve as an eraser seat 115 or socket, said magazine and head being formed of a single piece of tubing but of different diameters respectively.

6. In a mechanical pencil comprising a tubular barrel and a lead-feeding mechanism therein, a 120 bushing inserted in the writing end of the barrel, having means for arresting the feeding movement of the mechanism, and means for attaching a tip member to said bushing.

7. In a mechanical pencil comprising a tubular barrel and a lead-feeding mechanism therein, a bushing secured in the writing end of said barrel having an internal shoulder which serves as a stop for the lead-feeding movement of the mechanism, the bushing itself providing a bearing for centering the rotating part of the mechanism in the barrel, and said bushing including an extension beyond the barrel formed to receive a detachable tip for the pencil. 125

8. In a mechanical pencil comprising a tubular barrel, a lead-feeding mechanism including a longitudinally slotted tube, a lead holder and a lead expeller functioning therein, a bushing fixed in the writing end of the barrel, said mechanism also including a shouldered part stopped against 130 the opposite end of the barrel, said slotted tube extending through said bushing and beyond it, and a nut on said extending portion of the tube securing the latter in operative position. 140

9. In a mechanical pencil comprising a tubular barrel, a lead-operating mechanism including a lead tube in the barrel threaded as its lower end with a nut thereon, the barrel having a tubular bushing disposed at the writing end and the lead tube extending through said bushing, together 145

- with a washer on the tube between the bushing and the nut, and means on the mechanism engaging the barrel to check the mechanism and said lead tube against movement toward the writing end of the pencil while permitting rotation of the mechanism about its axis in the barrel.
10. In a mechanical pencil comprising a barrel with a lead-operating mechanism therein which includes a lead tube extending beyond one end of the barrel, and a head protruding from the opposite end thereof, said head including a transverse shoulder stopped against the upper end of the barrel, and a check nut screwed onto the lower end of the lead tube and stopped against the lower end of the barrel, together with a hollow tip secured to the lower end of the barrel enclosing said nut.
11. In a mechanical pencil comprising a barrel of celluloid or the like shrinkable material, a flanged bushing secured slidably in the bore of
- the barrel at its upper end, a threaded bushing fitted tightly in the bore of the barrel at the lower end with its threaded portion protruding therefrom, a lead-operating mechanism extending throughout the barrel and provided with a head having a transverse shoulder abutting the flange of the bushing at the upper end, said mechanism including a part which protrudes from the bushing at the lower end of the barrel, said protruding part being threaded, and a stop nut adjustably screwed thereon, together with a hollow tip forming an extension of the barrel and threaded for securing on the threaded protruding portion of the bushing at the lower end of said barrel, whereby said tip is removable to afford access to the nut for dismantling the mechanism or adjusting it to take up wear or compensate for shrinkage of the barrel.
